UNITED STATES PATENT OFFICE.

SILAS E. NORTON, OF EAST ORWELL, OHIO.

ADJUSTABLE WINDOW SCREEN.

Application filed June 21, 1922. Serial No. 569,980.

To all whom it may concern:

Be it known that I, SILAS E. NORTON, a citizen of the United States, residing at East Orwell, in the county of Ashtabula and State 5 of Ohio, have invented new and useful Improvements in Adjustable Window Screens, of which the following is a specification.

This invention relates to window screens and has for its object the provision of a novel 10 all metal screen which is adjustable to fit windows of different sizes, the construction being such that the adjustment may be made very easily and without the employment of any tools.

15 An important object is the provision of a screen of this character which is provided with a species of flap for the purpose of excluding flies at the point where the sash engages the upper edge of the screen.

20 Another object is the provision of a screen of this character which is located in the space between the parting strips and the blind stops and which is provided with spacing lugs engaging the blind stops. It being 25 moreover intended that the sides of the screen be secured to the jamb casings so as to prevent any possibility of removing the screen from the outside of the window.

30 An additional object is the provision of a screen of this character which will be simple and inexpensive in manufacture, and installation, efficient and convenient in use, durable in service and a general improvement in the art.

35 With the above and other objects and advantages in view the invention consists in the details of construction to be hereinafter more fully described and claimed and illustrated in the accompanying drawings, in 40 which:

Figure 1 is a view of a window showing my screen in place,

Figure 2 is a horizontal section through the screen and window structure,

45 Figure 3 is a vertical section and the remaining figures are detail views.

Referring more particularly to the drawings the letter A designates a window frame having the usual jambs B, sills C, blind 50 stops D and parting strips E. The sashes are represented by the letter F.

55 In carrying out my invention I provide a screen which consists of two rectangular sections 10 which are similar and each of which is of angle bar formation. One section telescopes within the other as clearly shown so

that the width of the screen may be varied so as to fit windows of different sizes. It is intended that the width of the angle bars be of sufficient size to hold the screen in a 60 rigid position when placed with its sides engaging against the confronting faces of the jamb casings. The opposite sides of the sections are provided with holes 11 for the passage of suitable screws 12 which pass into 65 the jamb casings for holding the screen rigidly in place in such manner that it could not be removed from the outside by a would be intruder.

The wire screen 13 is placed against the 70 inner faces of the angle bars forming the sections and is secured by soldering, brazing or by any other preferred method, the advantage of this construction being that it is unnecessary to bend the screen wire. 75

Secured to the underside of the top flanges of the sections are strips 14 of wire screen which overlap as shown and which have their edges bound with fabric as indicated at 15.

In order that the screen may be properly 80 braced with respect to the window structure I provide lugs 16 secured to or formed integrally upon the opposite sides of the sections and extending to the blind stops D.

In installing the screen, the sections must 85 first be pushed together sufficiently to permit insertion of the screen between the parting strips, after which the sections are pulled apart to bring the sides of the screen in firm engagement with the jamb casings, 90 the screen being so arranged that the lugs 16 will engage the blind stops D. The screws 12 are then inserted and the screen will then be held rigidly in place and will be outwardly of the lower sash so that the 95 window may be opened and closed at will without interference with the screen. The fabric bound strips 14 bear against the outside of the lower sash and serve to exclude flies or other insects which might attempt 100 to enter the room.

From the foregoing description and a study of the drawings it will be apparent that I have thus provided a simply constructed and consequently inexpensive 105 screen which is not only adjustable to fit windows of different sizes but which is also mounted in a peculiar manner so as to have the proper rigidity for preventing it from being blown out in case of a heavy wind 110 storm and also to prevent it from being removed by an intruder working from the

outside. Another feature of advantage is that the screen does not interfere with the action of the sash so that the window may be opened and closed at will without it being necessary to remove the screen.

While I have shown and described the preferred embodiment of the invention it is of course to be understood that I reserve the right to make such changes in the form, construction and arrangement of parts as will not depart from the spirit of the invention or the scope of the subjoined claims.

Having thus described my invention I claim:

1. An adjustable window screen comprising a pair of similar rectangular screen covered frame sections disposed in telescoped overlapping arrangement and disposed between the sides of a window casing

with the frame sections engaging the parting strips thereof, and lugs on the frames bearing against the adjacent faces of the blind stops for holding the frame sections against lateral displacement.

2. An adjustable window screen comprising a pair of rectangular screen covered frame sections disposed in telescoped overlapping arrangement and adapted for disposition between the sides of a window casing between the parting strip and blind stop, and a plurality of lugs on the frame sections adapted to bear against the blind stops for holding the frame sections against lateral displacement.

In testimony whereof I affix my signature.

SILAS E. NORTON.
